UNITED STATES PATENT OFFICE

2,474,197

ELECTROMAGNETIC SOUND POWERED TELEPHONE

Glenn L. Dimmick, Haddonfield, N. J., assignor to Radio Corporation of America, a corporation of Delaware

Application May 31, 1940, Serial No. 338,057

5 Claims. (Cl. 179—115)

1

This invention relates to sound-powered telephones, and more particularly to a telephonically transducer adapted to act either as a transmitter or to generate electrical oscillations in response to acoustical energy, or as a receiver to translate electrical oscillations into acoustical vibrations.

The principal object of my present invention is to provide a transducer as aforesaid having improved efficiency and ruggedness over similar devices heretofore known.

More particularly, it is an object of my present invention to provide an improved transducer as aforesaid in which the high frequency response is extended over a wider range than heretofore.

Another object of my present invention is to provide an improved transducer as set forth above which will not be subject to damage upon sudden and excessive changes in air pressure in the vicinity of the diaphragm thereof.

A further object of my present invention is to provide an improved transducer of the type set forth above which is simple in construction, and which readily lends itself to economical manufacture.

In accordance with my present invention, I provide the transducer with a more or less conventional electromagnetic motor or generator, as the case may be, and form the coupling rod which couples the armature of the magnetic unit to the diaphragm with a compliance in the form of an elastic link. This results in a three-peak system instead of the two-peak system previously known, the third peak extending the high frequency range considerably. Behind the diaphragm, an annular backing plate may be placed to protect the diaphragm from excessive deflection, the space between the backing plate and diaphragm being approximately of the same order as the width of the air gap in which the armature of the aforementioned unit operates. Also, a pair of spacing rings, one in front and the other just behind the diaphragm, are provided to clamp the marginal portion of the diaphragm to hold it in place. The spacing ring immediately behind the diaphragm is preferably made wider to extend radially inwardly of the diaphragm a greater distance than the front spacing ring, and this gives added protection to the diaphragm against excessive deflection. To further prevent the diaphragm from damage by excessive deflection and to provide acoustic protection therefor, I provide a flap valve which is placed adjacent the front plate of the unit to cooperate with the perforations therein. Thus, normal air waves in the atmosphere will pass through the cover plate to

the diaphragm, but any sudden and excessive rise in pressure, such as that resulting, for example, from gun fire on a battleship, will close the valve against the cover plate and prevent excessive displacement of the diaphragm.

The novel features that I consider characteristic of my invention are set forth with particularity in the appended claims. The invention itself, however, both as to its organization and

method of operation, as well as additional objects and advantages thereof, will best be understood from the following description of several embodiments thereof, when read in connection with the accompanying drawing, in which

Figure 1 is a view partly in section showing a unit formed in accordance with certain features of my invention,

Figure 2 is a wiring diagram showing the electrical equivalent of the mechanical-acoustical system of Figure 1,

Figure 3 is a response curve of the system shown in Figure 1,

Figure 4 is a view similar to Figure 1 showing certain other features of my invention, and

Figure 5 is a fragmentary plan view of the device shown in Figure 4.

Referring more particularly to the drawing, wherein similar reference numerals designate corresponding parts throughout, I have shown, in Figure 1, an acoustic diaphragm 1 clamped at its marginal portion between a pair of clamping rings 3 and covered with a cover plate 5 having one or more openings 7 therein. Connected to the diaphragm 1 at one of its ends is a drive rod 9 which has its other end connected to an armature 11 of the cantilever type rigidly secured to a nonmagnetic insert 12 between a pair of pole pieces 13 and extending through an air gap 15 between the pole pieces 13, a magnet 17 supplying flux to the air gap 15. The drive rod 9 has an axis of motion and is movable freely along that axis. The drive rod 9 is also provided with an S-shaped or accordion-like link 19 which constitutes a compliance which is symmetrical with respect to the drive rod axis of motion, and which serves to extend the range of the unit approximately 500 cycles as shown by the response curve of Figure 3 wherein the dotted curve indicates the response of the previously known two-peak systems and the solid line represents the response of my improved three-peak system.

The effect of the elastic link or compliance 19 will be better understood by reference to Figure 2. If M_f represents the effective mass of the air in

the opening 7, C_f represents the elastance of the

air in the cavity between the cover plate 5 and the diaphragm 1, L_2 and C_2 represent the mass and the elastance of the diaphragm 1, respectively, L_3 and C_3 represent, respectively, the mass and elastance of armature 11, and C_4 represents the elastance of the link 19, then the relation in the corresponding electrical circuit will be as shown in Figure 2. It is the introduction of the elastance or capacitance C_4 in the system which results in the third peak shown at the extreme right in Figure 3.

Devices of the type herein described are used quite extensively on battleships for communication from one part of the ship to another. It frequently happens, upon the firing of a gun in the neighborhood of one of the units, that the sudden rise in pressure in front of the cover plate 5 resulting from the blast causes the diaphragm 1 to break as the result of excessive deflection. To prevent this, I provide the structure shown in Figures 4 and 5. In this form of my invention, the diaphragm 1 is clamped between a pair of rings 21 and 23, the latter of which engages the rear surface of the diaphragm and is wider than the former, thereby extending radially inwardly a distance greater than the ring 21. Resting against the ring 21 is a cover plate 25 which has a relatively thin, central region and a relatively thick, marginal portion 27, the central region of the plate 25 being provided with a plurality of openings or perforations 29 corresponding to the opening 7 of Figure 1. Clamped against the outer, marginal face of the cover plate 25 and spaced slightly from the central, perforated region thereof is a flap valve 31 which is provided with a plurality of perforations 33 staggered with respect to the perforations 29, the valve member 31 being held against the plate 27 by the inwardly extending flange 35 of a cap member 37 which is threaded onto a back plate 39. Also secured to the marginal portion 27 at the inner face thereof is a second flap valve 32 having a plurality of perforations 34 therein aligned with the perforations 33 and similarly staggered with respect to the perforations 29. The valve member 32 may be secured to the cover plate 25 by means of a clamping ring 36 and screws 38. Preferably, although not necessarily, the valves 31 and 32 may be made in the form of spiders having central circular portions and radially outwardly extending arms which are clamped against the cover plate, as clearly shown in Figure 5.

From the foregoing description, it will be obvious that, upon a sudden and excessive rise in air pressure in front of the cover plate 25 resulting, for example, from the blast of a gun, the outer valve 31 will be forced against the plate 25 to close the perforations or ports 29 therein through which normal acoustical air waves may pass freely to or from the diaphragm 1. Similarly, if there is a sudden rarefaction of air in front of the cover plate 25 resulting in a sudden and excessive decrease in air pressure, the valve 32 will close against the ports or perforations 29 on the other side of the plate 25 and again prevent abnormal displacement of the diaphragm 1, but this time in a forward direction. Since the diaphragm 1 is most apt to be unduly or excessively displaced in a rearward direction rather than a forward direction, additional precaution may be taken to safeguard the diaphragm by making the clamping ring 23 wider than the clamping ring 21 and by having the backing plate 39 extend radially inwardly of the diaphragm 1 a considerable distance, as clearly shown in Figure 4. The

stiffness of the edge of the diaphragm 1 for very small vibrations is determined by the width of the narrower spacing ring 21, but for large deflections toward the rear, the edge of the diaphragm is protected by the wider spacing ring 23. The backing plate 39 is sufficiently close to the fold 1a of the diaphragm 1 to form a support for the diaphragm after it has been deflected an amount slightly less than that permitted by the air gap 15. This greatly adds to the effective maximum strength of the diaphragm.

From the foregoing description, it will be apparent to those skilled in the art that I have provided an improved sound-powered telephone unit which is not only rugged in construction, but which is also responsive over a wider range than heretofore. The spiders or valves 31 and 32 are preferably made of thin metal. For any normal forces, such as those due to wind, the stiffness of the spiders is great enough to hold the central portions thereof away from the cover plate and to allow the voice or acoustical waves to act upon the diaphragm when the device is used as a transmitter. However, as noted heretofore, large forces, such as those due to gun fire, will cause one or the other of the spider flap valves to close against the cover plate and prevent damage to the diaphragm or other parts of the unit. After the blast of the gun fire is over, the unit is immediately ready for use again.

Although I have shown and described several forms of my invention, it will be apparent to those skilled in the art that many variations thereof are possible. I, therefore, desire that my invention shall not be limited except insofar as is made necessary by the prior art and by the spirit of the appended claims.

I claim as my invention:

1. A telephonic transducer comprising a vibratile member, an electromechanical unit including a movable element, and means coupling said movable element to said vibratile member, said means having an axis of motion and being movable freely along said axis, and said means having an accordion-like compliance therein symmetrical with respect to its said axis.

2. A telephonic transducer comprising a diaphragm, a reversible electromechanical unit including an armature, and means coupling said armature to said diaphragm, said means having an axis of motion and being movable freely along said axis, and said means having an S-shaped compliance therein symmetrical with respect to said axis.

3. A telephonic transducer comprising a diaphragm, a reversible electromechanical unit including an armature, and a driving rod connecting said armature to said diaphragm, said driving rod having an axis of motion and being movable freely along said axis, and said driving rod having an accordion-like link therein symmetrical with respect to said axis.

4. A telephonic transducer comprising a diaphragm, a reversible electromechanical unit including an armature, and a driving rod having one end connected to said diaphragm and its other end connected to said armature, said driving rod having an axis of motion and being movable freely along said axis, and said driving rod having an S-shaped link intermediate its ends which is symmetrical with respect to said axis.

5. A telephonic transducer comprising a vibratile member, an electromechanical unit including an armature, and means coupling said armature to said diaphragm, said coupling means having

an axis of motion and being movable freely along said axis, and said coupling means extending generally in a direction normal to said armature and including a portion which is compliant generally in said direction said compliant portion being symmetrical with respect to said axis.

GLENN L. DIMMICK.
